SAMPLE HOLDER

Martin Steinthal, New York, N. Y.

Application September 30, 1938, Serial No. 232,585

4 Claims. (Cl. 229—82)

This invention relates to improvements in sample holders and has for one of its objects to provide an improved holder of simple and practical construction wherein small fabric swatches and a larger quality sample of the goods contained in said swatches are combined in a unitary structure so that the same may be effectively displayed.

The above and other objects will appear more clearly from the following detailed description 10 when taken in connection with the accompanying drawings which illustrate the preferred embodiments of the inventive idea.

In the drawings:

Figure 1 is a perspective view of a sample holder 15 or binder constructed in accordance with one embodiment of the invention and shown in its closed position.

Figure 2 is a similar view showing the holder in its opened position.

Figure 3 is a section on the line 3—3 of Figure 1. 20 Figure 4 is a view similar to Figure 2 showing another form of holder.

Figure 5 is a top plan view of the holder of Figure 4 in its closed or folded position.

Figure 6 is a plan view, partly broken away, of 25 still another form of sample holder in its opened position, and

Figure 7 is a transverse section through the holder of Figure 6.

Referring more particularly to Figures 1 to 3, the numeral 10 indicates a mounting sheet upon which may be secured, in any preferred manner, a plurality of small swatches 11 which may be of different designs and of the same quality of fabric. The inner edge of the sheet 10 is provided with an inturned flap 12 and inserted between said flap and the opposed portion of the undersurface of the sheet 10 and secured thereto, by suitable adhesive, is one edge of a quality sample 13. This sample may have the same fabric design or pattern as any one of the small swatches 11 and is of the same quality of fabric as all of the swatches. The sample 13 is made of a size sufficient to enable a prospective purchaser to obtain a better idea of the quality of the fabric than can be secured from one of the small swatches 11 and, as shown in the drawings, is formed from a length of material that is folded upon itself with the free ends secured 40 between the sheet 10 and the flap 12. When so folded, the sample 13 is of an area substantially twice the size of the mounting sheet 10 so that one-half of the sample will completely cover the back of said sheet, while the remaining half, when 45 not extended as indicated by the dotted lines in

Figure 3, may be folded in and cover the front of the sheet 10 to which the swatches 11 are secured, as shown by the full line in Figure 3.

The folder further comprises a cover section 14 of substantially the same area of the sheet 10 and said cover section has a flap 15 secured, by adhesive, to the flap 12. Said cover section is then bent around the adjacent edge of the sheet 10 as indicated at 16 and said bent portion defines a folding line by means of which the cover section 10 is hingedly mounted for movement to opened and closed positions. The outer surface of the cover section 14 may be employed for the printing of suitable advertising indicia while the inner surface of said cover section may have secured thereto a plurality of swatches 17 similar to the swatches 11.

In the form of the invention illustrated in Figures 4 and 5, the holder is shown as comprising a mounting sheet 18 upon which may be secured 20 a plurality of sample swatches 19 similar to the swatches 11 and 17. A backing 20 is provided for the sheet 18 and interposed between said elements is a filler 21 which is secured to the inner opposed surface of said sheet and backing by a suitable 25 adhesive. The filler 21 is of less area than the sheet and backing so as to provide a space between the latter elements along their outer vertical edges for the introduction of the inner edge of the quality sample 22, similar to the sample 13. Said inner edge of the sample 22 is secured in 30 said space by an adhesive and when folded upon itself, as indicated, is of substantially the area of the sheet 18. When not being inspected, the sample 22 may be folded inwardly in superimposed relation to said sheet 18, as indicated in 35 Figure 5.

The holder further comprises a cover section 23 of the same size as the sheet 18 and preferably made of a transparent material, such as Celluloid, so that the sample 22 is visible through the cover section when the parts are in folded position. To secure the various elements together, a spiral binder 24 may be employed which extends through the sheet 18, backing 20, filler 21 and the 40 cover section 23 so that the latter element may be swung to opened and closed positions as shown in Figures 4 and 5, respectively.

Again, as in the previously described modifications, the holder of Figures 6 and 7 is shown as 50 comprising a mounting sheet 25 upon which may be secured a plurality of swatches 26, the same being disposed in overlapping relation in the present instance. The holder further comprises a quality sample 27 which, in the present embodiment, 55

ment, constitutes both the back and the front of the holder. For this purpose said sample 27 is made of a double thickness of the fabric and when so formed is of an area substantially twice 5 the size of the mounting sheet 25. One section 28 of the sample 27 forms the back of the holder while the other section 29 thereof constitutes the front of the holder. The top and bottom edges of the two sections 28 and 29 and the free vertical 10 edge of the section 28 are secured by the binding strips 30 and these strips are also utilized to secure to the inner surface of the section 28 a transparent cover 31 of Celluloid which combines with the latter section to form a pocket for receiving the mounting sheet 25 which may be removed from said pocket when it is desired to inspect the swatches 26.

What is claimed is:

1. A sample holder comprising a mounting sheet 20 having secured thereto a plurality of fabric swatches of like quality and each of different design, and a sample forming a part of said holder and extending beyond an edge thereof and being of greater area than the combined area of said 25 swatches and of the same quality, said sample

being foldable from said edge to constitute a cover for said swatches.

2. A sample holder comprising a mounting sheet having secured thereto a plurality of fabric swatches of like quality, a quality sample of at least substantially the area of said sheet secured to and covering the back of the latter and foldable over the swatches thereon, and a cover for said folder hingedly connected to said sheet.

3. A sample holder comprising a mounting sheet 10 having secured thereto a plurality of fabric swatches of like quality, a quality sample of at least substantially the area of said sheet secured to the latter and foldable over the swatches thereon, and a transparent cover for said folder hinged- 15 ly connected to said sheet.

4. A sample holder comprising a mounting sheet having secured thereto a plurality of swatches of like quality, a quality sample of substantially twice the area of said sheet and constituting a backing and a covering therefor, and a transparent sheet secured to a portion of said sample so as to combine therewith to form a pocket for receiving said mounting sheet.
